Primary Examiner—Terry A. Wallace
Assistant Examiner—C. Tuttle*Attorney, Agent, or Firm*—Sughrue, Mion, Zinn, Macpeak & Seas[57] **CLAIM**

The ornamental design for a hair coloring easel, as shown and described.

DESCRIPTION

FIG. 1 is a perspective view of the top, front and left side of a hair coloring easel showing my new design;

FIG. 2 is a right side elevational view thereof, the side opposite being a mirror image of the side shown; and, FIG. 3 is a rear elevational view thereof.

The bottom surface of the easel forms no part of the claimed design.
